UNITED STATES PATENT OFFICE.

ARCHIBALD B. MURRAY, OF SAN RAFAEL, CALIFORNIA.

EASEL-SUPPORT.

SPECIFICATION forming part of Letters Patent No. 686,417, dated November 12, 1901.

Application filed August 27, 1901. Serial No. 73,463. (No model.)

To all whom it may concern:

Be it known that I, ARCHIBALD B. MURRAY, a citizen of the United States, residing at San Rafael, county of Marin, and State of California, have invented certain new and useful Improvements in Easel-Supports; and I hereby declare the following to be a full, clear, and exact description of the same, reference being had to the accompanying drawings, forming 10 a part of this specification.

This invention relates to an improvement in easel-supports for pictures, cards, and the like.

My improvement consists in an easel-support 15 formed of a single and continuous piece of metallic wire bent to form the several members or parts of a simple and convenient easel-support that maintains an elastic grip upon cards or pictures supported thereby, as hereinafter more particularly described, and illustrated by drawings that form a part of this specification.

The object of my invention is to provide 20 easel-supports of such simple and inexpensive manufacture and convenience that their wider use can be permitted for mounting pictures, commercial cards, and similar uses, also the attainment in such supports of a form that permits their being packed in close 25 bunches and packages for commercial purposes.

To these ends I construct easel-supports as shown in the drawings now to be referred to.

Figure I represents in perspective a picture 30 mounted on one of my improved supports, the rear extension of the latter being indicated by dotted lines; Fig. II, an oblique or perspective rear view of Fig. I, and Fig. III a plan view of the easel-support detached.

As will be seen in the drawings, the easel-support 35 is formed of one continuous piece of metallic wire bent to rest at three points, A, B, and C, with a rear extension D, that forms a back support, and two upturned extensions E and F at the front of the picture or card G. These front extensions E and F, being set in alinement with the divergent members H and J and rendered elastic by the elastic arms of the duplex rear support D, grip and have a 40 slight tendency to curve the picture and card G

convexly on the front, which is desirable, also by elasticity of the wire will permit cards of different thickness to be inserted. This last-described feature is one of much convenience, because in moving or handling a picture or 55 card the easel-support adheres thereto and is so light in weight that it offers no impediment in moving the mounted articles for dusting or rearranging them, one hand only being required for this purpose. 60

The wire employed in constructing the easel-supports can be plain or plated and of any suitable metal. For photographs and ornamented cards it is preferably made of non-corrosive material and can be plated with 65 gold, silver, or nickel and the dimensions be adapted to the size and weight of the cards or pictures to be supported, the general form remaining the same.

For commercial uses—such as supporting 70 price-cards, advertisements, or articles of trade that are mounted on cards—the supports are made accordingly of heavier or lighter plain wire.

The rear extension D can be bent to change 75 the inclination of the picture or card G to any desired angle. The extensions E and F are preferably made short, so as to not obscure or disfigure the faces of articles when mounted. 80

Having thus described the nature and objects of my invention and the manner of making and applying the same, what I claim as new, and desire to secure by Letters Patent, is— 85

An easel-support, consisting of the duplex elastic rear support D, members H, J, diverging from said rear support and from each other and front extensions E, F, upturned in alinement with said members H, J, the whole 90 formed of a continuous piece of wire, substantially as specified.

In testimony whereof I have signed my name to this specification in the presence of two subscribing witnesses.

ARCHIBALD B. MURRAY.
